UNITED STATES PATENT OFFICE.

CHARLES E. TORRANCE, OF HOLYOKE, MASSACHUSETTS, ASSIGNOR TO B. F. PERKINS & SON, INC., OF HOLYOKE, MASSACHUSETTS, A CORPORATION.

PAPER-MACHINE.

1,161,806.

Specification of Letters Patent. Patented Nov. 23, 1915.

Application filed January 18, 1915. Serial No. 2,915.

To all whom it may concern:

Be it known that I, CHARLES E. TORRANCE, a citizen of the United States of America, and resident of Holyoke, in the county of 5 Hampden and State of Massachusetts, have invented certain new and useful Improvements in Paper-Machines, of which the following is a full, clear, and exact description.

10 This invention relates to improvements in a device for cleaning the wire of a Fourdrinier paper machine, that is the woven-wire endless apron on the upper course or run of which the pulp is carried in the course of 15 fabrication of the web. These aprons after a while become more or less clogged and impaired by specks of dirt, pitch, pulp and other matter so that it is a matter of desirability from time to time to clean the apron 20 for freeing it of the accumulations thereon and therein of the character above mentioned.

The object of this invention is to provide a device, for cleaning the wire apron of a 25 Fourdrinier paper machine, of improved character and one which may easily, and at pleasure, be so operated that the brush or cleaning member may be carried up to contact against the under or working side of 30 the lower course or run of the apron, and then after the work of cleaning thereby has been performed, to be as easily lowered away from its operative position. And another object of the invention is to provide an improved construction of a roller brush which 35 is especially applicable for employment in this wire apron cleaning device and which will not be affected in any detrimental way by the water and moisture to which it is subjected by reason of its coaction with the wire 40 apron.

The invention is described in conjunction with the accompanying drawings and is set forth in the claims.

45 In the drawings:—Figure 1 is a plan view of the device for cleaning the "wire" or endless apron of a Fourdrinier machine. Fig. 2 is a front elevation of the same. Fig. 3 is a front elevation showing the opposite 50 end portions of the device on a larger scale, Fig. 4 being a plan of one end portion and Fig. 5 being an end elevation of the same. Fig. 6 is a diagrammatic view showing the wire or endless apron and on which indication is made of a location relatively thereto

of the cleaner comprised in this new device. Fig. 7 is a central longitudinal sectional view of an improved construction of brush roll for use in the device. Fig. 8 is a cross sectional view of Fig. 7. 33

In the drawings, A A represent a pair of members adapted to be supported in any suitable manner and positioned in opposition beneath the lower course *a* of the wire apron B, each said member comprising an 35 upstanding post *b* having rack teeth *d* on its side.

C C represent collars fitted to slide vertically about said toothed posts having apertures *f f* through the sides thereof opposite 40 said rack teeth and provided with rearwardly extending journal projections *g* and with forwardly extending journal projections *h*. 70

The cleaner for the "wire," which may 45 be constituted by a brush roll E, has end journals thereof mounted in the opposed pair of journal projections *g g* of the said vertically slidable collar members C. 75

A position-controlling shaft G is mounted 50 in the other opposed pair of journal extensions *h h*; and this shaft opposite each of the posts has pinions *i* affixed thereon and extending through the apertures *f* and meshing with the rack teeth of said posts; and 55 said shaft also has a ratchet wheel *k* affixed thereon with which coacts a pawl *m* which is carried by the vertically slidable collar which is adjacent said ratchet wheel. The 60 shaft G has the crank handle *n* for rotatively 65 turning it. 90

By assuming that the device has the brush 70 thereof in the lowered position below and clear from the under-running course of the Fourdrinier wire apron and it is desired to 95 elevate the brush for its cleaning coaction with the apron, it is only necessary to turn the crank handle for a part of a revolution whereby through the action of the pinions 100 the vertically slidable collar members will be caused to climb or become elevated relatively to the posts *b* which serve as the guides and bearings. The elevation of the parts is to be such as to bring the brush roll to its proper operative action relatively to the 105 wire, which under the power of the paper machine giving its progression, induces the rotary motion to the brush for its cleaning action. 110

The pawl holds the device in the eleva-

tion to which it is most properly adjusted during the time the device is in operation, but after the work in a given time shall have been accomplished, the pawl is manually 5 thrown out of engagement with the ratchet wheel, and the collar members and the parts carried thereby are lowered so that for the most of the time and while not necessary, the brush is down and away from its working 10 position, when, of course, there is an avoidance of abrasive action between the brush and wire for unnecessarily wearing these equipments.

From the position in which the brush roll 15 of the cleaner is used, for instance one indicated by E*, or one indicated by E* in Fig. 6, the roll is wet most of the time, but usually about once a week there is an opportunity, when the machine is not running, for 20 the roll to dry out. These brush rolls have sometimes been made with wooden staves or lags carrying or holding the brass wire or other bristles of the brush, such staves have been secured by wood screws upon a wooden 25 central roll body or core.

The swelling and shrinking of the wooden staves and the wooden core have not only twisted the roll out of true, but have caused 30 loosening of the wood screws so that the roll would more or less go to pieces and the loosened screws would seriously damage the wire apron. To obviate these troubles, a construction of roll to be embodied in this 35 cleaning device has been devised and practically used according to the representation thereof given in Figs. 7 and 8, wherein it is seen that the same consists of a tubular core J advantageously made in the form of a wrought iron pipe open from end to end, 40 into which the cast iron heads o o are pressed, and which heads have formed integral therewith or fitted therein the end journal members p. The core receives in 45 completely encircling relation thereabout a plurality, four, more or less, of wooden staves t, cross sectionally of segmental or arc shape to conform circumferentially to the core and which staves carry the wire bristles u. The staves are secured to the 50 core by machine screws v, the heads of which are countersunk into the staves, and the shanks of which extend through said staves and with screw thread engagements into holes therefor in the tubular metal core.

55 This construction of roll is one which has been found to be simple, practicable and inexpensive of construction, but as more especially important, has also proved most efficient and satisfactory as the wire apron 60 cleaning element of the device.

I claim:

1. In a device for cleaning the wire apron of a Fourdrinier paper machine, in combination, a pair of members adapted to be 65 positioned in opposition beneath the lower

course of the wire apron, each said member comprising an upstanding post having teeth on its side, members vertically slidable relatively to said toothed posts, a wire apron cleaner supported by and between said members, and a position controlling device for, and carried by, said slideable members, including a shaft having gear wheel connections with said toothed posts and means for holding said shaft locked against accidental 75 rotation.

2. In a device for cleaning the wire apron of a Fourdrinier paper machine, in combination, a pair of members adapted to be positioned in opposition beneath the lower 80 course of the wire apron, each said member comprising an upstanding post having rack teeth on its side, members vertically slidable relatively to said rack toothed posts, comprising journal supports for a brush roll, and journal supports for a position controlling shaft, a brush roll mounted in one set of said journal supports, and a position controlling shaft mounted in the other set of said journal supports, and having pinions 90 affixed thereon in mesh with the rack teeth of said posts, and provided with means for rotatively moving it, and means for holding said pinion provided shaft against rotation.

3. In a device for cleaning the wire apron of a Fourdrinier paper machine, in combination, a pair of members adapted to be positioned in opposition beneath the lower course of the wire apron, each said member comprising an upstanding post having 100 rack teeth on its side, members vertically slidable relatively to said rack toothed posts, comprising journal supports for a brush roll, and journal supports for a position controlling shaft, a brush roll mounted in one set 105 of said journal supports, and a position controlling shaft mounted in the other set of said journal supports, having pinions affixed thereon in mesh with the rack teeth of said posts, having a ratchet wheel affixed thereon, 110 and provided with means for rotatively moving it, and a pawl carried by one of said vertically slideable members coacting with said ratchet wheel.

4. In a device for cleaning the wire apron of a Fourdrinier paper machine, in combination, a pair of members adapted to be positioned in opposition beneath the lower course of the wire apron, each said member comprising an upstanding post having teeth on its side, members vertically slidable relatively to said toothed posts, an apron-cleaning brush roll supported by and between said members, and constructed with a tubular metal core, provided with end heads having journals to be mounted in said slideable members, wood brush-carrying staves of segmental form, fitted about and surrounding said tubular metal core, and headed machine screws connecting said staves to said tubular 125 130

metallic core, and a position controlling device for, and carried by, said slideable member, comprising a shaft having gear wheel connections with said toothed posts and means for holding said shaft locked against accidental rotation.

5. A brush roll consisting of a tubular metal core provided with endwise extended journals, wood brush carrying staves of segmental form fitted about and surrounding said tubular metal core, and machine screws the heads of which are countersunk in said staves and the shanks of which extend through said staves and with screw thread 10 engagements into said tubular metallic core.

6. In a device for cleaning the wire apron of a Fourdrinier paper machine, in combination, a pair of members adapted to be positioned in opposition beneath the lower course of the 15 wire apron, each said member comprising an upstanding post having rack teeth on its side,

collars vertically slidably fitted about said rack toothed posts, having apertures therein opposite the rack teeth of the adjacent posts, and provided with rearwardly and forwardly extending journal projections, a brush roll mounted in one set of journal extensions and a shaft, mounted in the other set of said journal extensions, having pinions affixed thereon, and extending through 20 said apertures and meshing with the rack teeth of said posts, and also having a ratchet wheel affixed thereon, means for rotatively moving said pinion provided shaft, and a pawl carried by one of said vertically slideable collars coacting with said ratchet wheel.

Signed by me at Holyoke, Mass., in presence of two subscribing witnesses.

CHARLES E. TORRANCE.
